UNITED STATES PATENT OFFICE.

BENJAMINE HENRY PURDY, OF DOUGLASS, KANSAS, ASSIGNOR OF THREE-FOURTHS
TO CARL McGREGOR AND C. A. WATSON, BOTH OF WINFIELD, KANSAS.

PIPE WRENCH.

Application filed August 9, 1927. Serial No. 211,773.

This invention relates to new and useful improvements in pipe wrenches and aims to provide a wrench equipped with a sliding jaw that may be adjusted in a rapid and easy manner and by the employment of but one hand and while the wrench is in position upon the work. Furthermore, the invention aims to provide rapid and positive means for locking the sliding jaw in adjusted position and this merely by releasing the sliding jaw carrier that is equipped at its lower end with a finger piece that extends alongside of the handle of the wrench and that may be engaged by the fingers of the hand holding the handle so that the locking and adjusting operation may be performed directly at the work.

The invention further aims to provide a pipe wrench of this character that is of relatively simple construction and inexpensive of manufacture, the same embodying few parts, and these so correlated as to reduce the possibility of disarrangement to a minimum.

In the drawing wherein like reference characters indicate corresponding parts of the same throughout the several views:

Figure 1 is a side elevation of my improved pipe wrench.

Figure 2 is a view partially in longitudinal section and partially in elevation.

Figures 3 and 4 are detail horizontal sections taken substantially on the line 3-3 and 4-4, respectively, of Figure 1 and looking in the direction of the arrows, and

Figure 5 is a fragmentary longitudinal section taken through the upper end of the sliding jaw carrier for more clearly disclosing the manner of association of the rigid jaw with said carrier, which rigid jaw also affects a locking means for the sliding jaw.

Now having particular reference to the drawing my novel pipe wrench consists of a handle 5 of suitable length that is formed at its upper end with an inwardly curved nose portion 6, the inner end of which is of rounded contour and provided with spaced teeth 7. Said upper end of said handle 5 is arranged within a sliding and rigid jaw carrier 8 that comprises a pair of spaced and somewhat elongated side walls 9-9, which side walls are of greater width at the upper end of the carrier and integrally joined by a wall 10 serving to provide a guide sleeve 11 through which is slidably arranged the shank 12 of a sliding jaw 13. This jaw shank 12 is pro-

vided at one face with an elongated channel 14 terminating within the ends of the shank and within which is arranged a pin carrying set screw 15 threaded within an opening in one side wall of the carrier 8 at the portion thereof comprising the side wall of said sleeve 11, see Figure 1.

The upper edges of the side walls 9-9 of said carrier 8 beneath the sliding jaw 13 are inclined downwardly and bent inwardly to provide flanges 9'-9'. Arranged upon the upper edges of said carrier side walls is a complementary stationary jaw 16, the bottom surface of which is cut upon an angle similar to the angle of the upper edges of said carrier side walls as clearly indicated in Figure 2. The inner face of this jaw is toothed as at 17. Formed integrally with the bottom surface of this jaw 16 is a pair of spaced depending lugs 18-18 that are formed at opposite sides directly beneath the bottom surface of the jaw 16 with slots for receiving the flanges 9'-9' of said carrier walls 9-9, see Figure 5. This character of connection between the stationary jaw and the carrier will permit the jaw to be slid outwardly or inwardly with respect to the shank 12 of the sliding jaw 13. Furthermore, the inner end of the jaw 16 is pointed to provide a locking tongue 19 adapted for engagement between teeth 20 formed upon the inner edge of the shank 12 of said sliding jaw 13.

At the inner nosed end of the lever 5 there is formed an oblong opening 21 that is arranged on an angle to the handle substantially equivalent to the angle of the inwardly bent end of the handle 5 that provides said nose 6, while arranged through this hole is a pivot pin 22 affixed at its ends to the side walls 9-9 of the carrier 8. Adjacent the lower edges of the side walls 9-9 of said carrier are registering arcuate shaped openings 23-23, these openings extending at an angle to the handle reverse to the angularity of the opening 21 in the nosed end of said handle 5. The handle 5 directly adjacent its inner edge carries a pin 24, the ends of which have sliding engagement through said registering openings 23-23.

Directly inwardly of the inner edge of the sliding jaw shank 12 the lower end of the carrier 8 is formed with a depending and somewhat outwardly curved finger lever 25, between which and the handle 6 is an expan-

sible coil spring 26 that serves to normally swing the carrier into the position disclosed in Figures 1 and 2, in which position the teeth 7 of the lever nose 6 will have engagement 5 with the teeth 20 of the sliding jaw shank 12. However, a pull upon the finger lever 25 will cause the nose 6 of the lever 5 to move away from the shank 12 of the jaw 13 and thereby be released therefrom. In order to 10 release the inner pointed end of the stationary jaw 16 from the shank 12 of said sliding jaw 13 the upper end of the lever 5 directly in back of the teeth 7 is provided with a lug 27 for engagement between the lugs 18—18 of 15 said jaw 16, the space between said lugs 18—18 being greater than the width of the lug 27 so that the same may have a slight movement therebetween without causing the sliding movement of the jaw 16 in reverse direction. Obviously as the finger lever 25 is 20 drawn inwardly so that the teeth 7 of the handle will be withdrawn from the teeth of the sliding jaw shank, the lug 27 of the handle 5 will engage the outermost lug 18 of the jaw 25 16 and slide the same away from the shank of the stationary jaw so that said stationary jaw may be moved inwardly or outwardly. A release of the finger lever 25 will immediately cause the return of the carrier which will 30 force the inner end of the lever 5 to the position disclosed and then when a pull is directed toward the right, is made upon the handle 5 the teeth 7 of the nose of the handle having mesh with the teeth of the sliding jaw shank 35 will tend to pull the jaw inwardly so that the

same will firmly bind the work between the jaws 13 and 16.

It will thus be seen that I have provided a highly novel, simple, and extremely efficient pipe wrench that is well adapted for all the 40 purposes heretofore designated, even though I have herein shown and described the invention as consisting of certain detail structural elements it is nevertheless to be understood that some changes may be made therein without affecting the spirit and scope of the appended claim. 45

Having thus described the invention, what I claim as new and desire to secure by Letters Patent is:—

In a wrench of the character described comprising a handle having a laterally disposed end portion, said end portion being provided with rack teeth, a projection on said end of the handle, a carrier pivoted to the said end 50 portion of the handle through a slot therein, a jaw structure on said carrier, a pair of inwardly disposed and spaced protuberances on said jaw structure, a slide jaw provided with a shank having rack teeth, the teeth of the 55 handle being engageable with the teeth of the shank for moving the slide jaw, the slotted end portion of the handle being adapted to be moved inwardly on the pivot and swung in a direction to cause the pressing of the projection against one of the protuberances and causing a binding action of the carrier jaw with the rack teeth of the shank. 60 65

In testimony whereof I affix my signature.

BENJAMINE HENRY PURDY.
